UNITED STATES PATENT OFFICE.

WILLIAM V. JUDSON, OF THE UNITED STATES ARMY.

STRUCTURE FOR USE IN HYDRAULIC ENGINEERING.

SPECIFICATION forming part of Letters Patent No. 670,821, dated March 19, 1901.

Application filed December 20, 1900. Serial No. 40,570. (No model.)

To all whom it may concern.

Be it known that I, WILLIAM V. JUDSON, captain in Corps of Engineers, United States Army, stationed at Montgomery, in the county 5 of Montgomery and State of Alabama, have invented certain new and useful Improvements in Structures for Use in Hydraulic Engineering; and I do hereby declare the following to be a full, clear, and exact description of the invention, such as will enable others skilled in the art to which it appertains to make and use the same.

My invention relates to improvements in structures for use in hydraulic engineering, 15 such as foundations in water, revetments, piers, retaining-walls, and the like.

The said invention consists in a combination of metal or wood with concrete or other masonry so arranged in combination with air-spaces as to form a construction that will possess flotation or which can easily be floated by means of auxiliary floats, so that said construction may easily be assembled upon the land or upon a floating vessel and launched 20 therefrom and then towed or propelled into position over a prepared or natural foundation, where it may be sunk either by the admission of water into the air-chambers or by the addition of weights. When sunk, my invention is designed to form part of a pier or retaining-wall or a foundation or to cover a portion of the bottom of a body of water and prevent erosion therefrom, due to waves or currents.

35 Figure 1 represents a sectional view of one form of my invention, the section being along the line 1 4 of Fig. 2. Fig. 2 represents a section along the line 2 2 of Fig. 1. Fig. 3 represents a section along the lines 3 3 of Figs. 40 1 and 2. Fig. 4 represents a similar section to that shown in Fig. 1, except that an inlet and air-pipes are provided for purposes hereinafter described. Fig. 5 represents a transverse section of a modified form of the device, 45 the section being along the line 5 5 of Fig. 6; and Fig. 6 represents a section along the line 6 6 of Fig. 5.

In all the various figures similar letters refer to corresponding parts.

50 A represents concrete or other masonry. B represents a metallic or wooden stiffener.

C represents a void or air-space within the structure.

D represents a pipe inserted in the structure. 55

E represents a valve or sea-cock.

F represents an air-cock.

G represents the end of a pipe to which a pump may be attached.

H, Fig. 6, represents a hand-line adapted to 60 operate any convenient tripping device H', which releases the end a of the beam pertaining to the removable bottom A' of the caisson and allows said beam to swing up about the opposite end a', releasing the bottom plank 65 and permitting the influx of water, mud, or sand at the desired moment.

A², Fig. 6, represents the upper head of the caisson, which may or may not be used. The lower edge of the caisson (shown in Fig. 6) is 70 preferably pointed somewhat, as at a², to allow it to cut more readily into the earth or sand as the caisson descends.

Referring to Figs. 1, 2, and 3, the device may be constructed either slightly heavier 75 than the water it replaces, in which case it would have to be supported by floats until it reached the point of its destination, where it is released and allowed to sink, or it may be made slightly lighter than the water it replaces, and water may be admitted by sea valves or cocks similar to those shown in Fig. 4 when it is desired to sink the caisson, the air being released through the cocks shown, or the sinking may be accomplished by the 80 addition of weights.

In the form of the device shown in Fig. 4 85 D represents a pipe controlled by the sea-cock E. This form of caisson is made lighter than the water it displaces and is towed to the 90 point of its destination, when if water be admitted through the sea-cock E into the pipe D and thence through openings into the void C and the cocks f be open the caisson will sink. If it is desired to subsequently lift the 95 caisson, the sea-cock E may be closed, the water pumped out of the chambers C by means of a pump attached to the pipe D at G, and the caisson will float.

In the form of the device shown in Figs. 5 100 and 6 the caisson is shown as cylindrical, though it may be made hexagonal or other

shape, if desired, and it is provided with pipes G D, extending down through the walls of the caisson to or through the bottom edge thereof, and water under pressure is forced through these pipes, causing the sharpened edges a^2 5 to settle or sink in the earth or sand until the caisson has reached the required depth and bearing. The bottom A' may be permanently secured in the caisson, in which case the erosion of the water through the pipes G D will 10 only carry the caisson down to about the height of the bottom A' above the base a^2 of the caisson, or this bottom may be made removable, as shown, and used merely to keep 15 water out of the caisson, and thus give it the requisite buoyancy while it is being floated to its destination.

The top A ^{2} , it will be obvious, may be omitted from the caisson altogether or may be put 20 in place either before the caisson has left the shore or after it has been partly submerged. It is also obvious that the top over the voids may be omitted in the form shown in Figs. 1, 2, and 3. Thus the caisson may have a fixed 25 or a removable bottom and be constructed with or without a top. Where no top is used, the caisson may be filled in and the foundation built on the top of the filling and the surrounding cylinder.

30 It will be obvious that the pipes G D may be omitted and the caisson with the removable bottom may be towed or otherwise transported to its destination, and when "placed" the bottom may be tripped and the caisson 35 allowed to sink of its own weight, and afterward weights may be piled on the top of the caisson, causing it to sink still farther, if desired.

It will be obvious that any of the various 40 caissons herein described may be either towed by or carried on another vessel and may be launched from the latter, if desired; also, that weights placed on the top of the caisson may be used to submerge the same in place of 45 filling the chambers with water, if preferred.

The sinking of a sufficient number of these caissons would provide a suitable foundation for lighthouses or the like, while the sinking of a number of these caissons in line would 50 be adapted to the forming of a pier, breakwater, or retaining-wall.

In any of the above methods it will be noted that a durable and easily-placed structure is secured, which combines great structural 55 strength with comparative cheapness.

It is the office of the metallic or wooden stiffeners to act by special virtue of their tensile strength, while the concrete or other masonry furnishes the necessary weight, surface 60 areas, and resistance to compressive stresses.

The various advantages of the herein-de-

scribed invention will readily suggest themselves to any competent engineer.

Having thus described my invention, what I claim, and desire to secure by Letters Patent 65 of the United States, is—

1. A caisson or similar structure, comprising a mass of concrete, with stiffeners embedded therein, arranged to provide air-chambers or voids, so that flotation may be availed 70 of to introduce the caisson into position as part or all of a foundation, breakwater, pier, retaining-wall or revetment, substantially as described.

2. In a caisson or similar structure, the 75 combination with a mass of concrete, with stiffeners embedded therein, the said mass being hollowed into chambers or voids so that the same may be floated, and a pipe or pipes with suitable valves and connections whereby the caisson may be sunk when and where desired, or raised again by filling the hollow chambers with water, or emptying the same, substantially as described.

3. In a caisson, or similar structure, the 85 combination of metallic or similar stiffeners with concrete or other masonry, so disposed about air-chambers, or voids, that flotation may be availed of to introduce the caisson into position as part or all of a foundation, 90 breakwater, pier, retaining-wall or revetment, and a pipe or pipes designed to convey water under pressure from above the general surface of the water to a point or points near the base of the structure, to act as a jet or 95 jets, and thus to sink the caisson into the earth or sand, substantially as described.

4. In a caisson, or similar structure, the 100 combination of metallic or similar stiffeners with concrete or other masonry, so disposed about air-chambers, or voids, that flotation may be availed of to introduce the caisson into position as part or all of a foundation, 105 breakwater, pier, retaining-wall or revetment, and a removable bottom of wood or other material designed to assist in flotation to the point of final location, but then to be removed to permit the penetration of the sides of the structure into the bottom of the lake, river or bay, substantially as described. 110

5. A caisson or similar structure provided with a removable bottom, and a tripping device operated from the top of the caisson for releasing said bottom and allowing the buoyant effect of the water to remove the same, 115 substantially as described.

In testimony whereof I affix my signature in presence of two witnesses.

WILLIAM V. JUDSON.
